MICROPHONE

George Bruce Kamp, Springfield, Pa., assignor to The Astatic Corporation, Conneaut, Ohio, a corporation of Ohio

Application October 10, 1957, Serial No. 48,057

Term of patent 7 years

(Cl. D26—14)

FIG. 1

FIG. 2

FIG. 3

FIG. 4

FIG. 5

Figure 1 is a top plan view of a microphone, showing my new design;

Figure 2 is a front elevational view;

Figure 3 is a side elevational view, the opposite side having substantially the same appearance;

Figure 4 is a rear elevational view; and

Figure 5 is a bottom plan view thereof.

I claim:

The ornamental design for a microphone, as shown and described.
